CARTRIDGE BELT LINK

Alonzo F. Gaidos, Redwood City, Calif., assignor
to the United States of America as represented
by the Secretary of War

Application April 4, 1946, Serial No. 659,639

5 Claims. (Cl. 89—35)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to an ammunition belt and more particularly to improved construction of the links that are assembled with cartridges to form the belt.

The invention relates specifically to that type of ammunition belt in which a series of like links are articulately connected by a series of cartridges to provide an ammunition belt of the disintegrating type. Each link comprises a body having a single connecting loop at one side thereof and a pair of coaxially spaced apart cartridge-receiving loops at the other side thereof on an axis paralleling the axis of the single or connecting loop. The spaced apart loops receive coaxially therebetween the single loop of an adjacent link, and a cartridge passed through the loops thus aligned serves as a pintle and articulately interconnects a pair of adjacent links. A series of similar connections are made and a belt of substantial length is thus made up. In the feeding of the belt through a weapon such as a machine gun, the cartridges are individually removed from the belt by the gun mechanism and fired. The belt disintegrates as individual links are progressively disconnected as the ammunition is being expended in firing.

With regard to the feeding of an ammunition belt to a machine gun and the extraction and firing of cartridges therein, there are two basic types of weapons: in one the cartridge is first extracted by being pulled rearwardly from the belt and is then moved forwardly into the gun chamber. In the other, the cartridge is simultaneously pushed forwardly through the belt and into the chamber of the gun. In the former type of gun, it is common to employ an ammunition belt made up of links in which all the loops are substantially completely circular. In the latter type weapon, the links comprising the belt have loops that are arcs of slightly more than 180°. The invention is concerned primarily with an ammunition belt of the latter type.

It is a characteristic of this type of ammunition belt that the links are adaptable for use in either of the types of weapons referred to above. In links of this type, certain problems arise with respect to the location of the cartridges in the belt. For example, the cartridges must be axially parallel and their base and nose portions must be respectively aligned. Inaccuracy in the loading of the belt in either of the foregoing respects

causes interference with the feeding mechanism of the weapon and this results in serious stoppages that prevent firing. It has been the practice heretofore to provide locating means on the links to assist in defining the proper location of the cartridges axially with respect to the links. Such means usually consists of a locating finger or portion formed on one or both of the double or cartridge-holding loops. However, it has been found that such means ordinarily interfere with extraction of the cartridge, whether such extraction be rearwardly by pulling or forwardly by pushing.

It is accordingly a principal object of the present invention to provide a belt link having improved cartridge-locating means and specifically to provide such means that is capable of accurately locating the cartridge in the link and yet will not adversely effect the extracting function of the weapon.

It is an important object of the invention to provide the cartridge-locating means on the single loop of the link and thus to accomplish a locating means that has increased cartridge-holding capacity and also increased resiliency that permits easy extraction of the cartridge.

The invention has for a further object the provision of such cartridge-locating means constructed and arranged to overlie and bridge one of the double loops of an adjacent link when the belt is assembled.

Still another object of the invention is to provide locating means as defined above in conjunction with a belt link having external circumferential reinforcing ribs and to provide the locating means in such a manner as to accommodate one of the double loops of an adjacent link without interfering with the free flexibility of the assembled belt.

And still another object of the invention is to provide two forms of belt link, in one of which the locating means cooperates with a rear or base portion, preferably the extracting groove, of a cartridge to assist in locating the cartridge in the link; and in another of which the locating means extends forwardly and cooperates with the shoulder cone at the neck of the cartridge to provide a seat that defines the position of the cartridge in the link.

A complete understanding of the foregoing and other desirable objects and features of the invention may be obtained from the following detailed description taken in conjunction with the accompanying sheet of drawings in which:

Fig. 1 is a plan view of a portion of an ammu-

tion belt embodying a link constructed according to one preferred form of the invention in which the locating means seats in the extracting groove of the cartridge.

Fig. 2 is a sectional view taken longitudinally through a pair of adjacent links as viewed along the line 2—2 of Fig. 1;

Fig. 3 is a view similar to Fig. 1 but showing that form of the invention in which the locating means cooperates with a forward portion of the cartridge;

Fig. 4 is a sectional view taken longitudinally through a pair of adjacent links as viewed along the line 4—4 of Fig. 3; and

Fig. 5 is an end view of the Fig. 3 link per se.

Fig. 6 is a plan view of the Fig. 1 link per se.

The ammunition belt of Fig. 1 is made up of a plurality of like links 10, each of which is provided with a single hinge or connecting loop 11 formed at one side of an intermediate body or bridge portion 12. A pair of coaxially spaced apart cartridge-holding loops 13 and 14 is formed integral with and disposed at the other side of the body 12 on an axis paralleling the axis of the loop 11. As shown in Fig. 1, when the ammunition belt is assembled from a plurality of links 10, the single or hinge loop 11 of one link is positioned coaxially between the double loops 13 and 14 of an adjacent link. A cartridge 15, illustrated diagrammatically in Fig. 1, is passed through the three loops 11, 13 and 14. Each of the loops 13 and 14 substantially tightly and resiliently grips the cartridge case. The loop 11 is formed so that it grips the cartridge case relatively loosely to provide a hinge or pintle for free pivotal movement between adjacent links that contributes to the desired flexibility of the entire belt. In a preferred form of the invention, the loop 13 is reinforced by a pair of axially spaced, external, circumferential ribs 16 and the loop 14 is similarly reinforced by a pair of similar ribs 17. The reinforcement contributes to the capacity of the loops 13 and 14 for gripping the case of the cartridge 15.

The loops 11, 13 and 14 are of the so-called open type, and the arcuate extent of each is relatively slightly greater than 180°, reference being had to the illustration in Fig. 5. Links of this type are adapted for use in weapons of either of the types heretofore referred to and carry cartridges for extraction either rearwardly by pulling or forwardly by pushing.

In order that the cartridges may be loaded accurately into the assembled belt, each link 10 is provided with means for defining the axial extent to which a cartridge will be inserted through the link loops. According to the form of invention shown in Fig. 1, the cartridge-locating means comprises a rearwardly extending locating finger 18 provided at its free or rear end with a crimped portion 19 shaped to fit the extracting groove of the cartridge 15. In Fig. 1 the extracting groove is indicated by the numeral 20. As best shown in Fig. 2, the locating finger 18 is provided intermediate its ends with a pair of axially spaced transverse grooves 21, preferably formed as indentations in the finger, serving to accommodate or interfit with the external circumferential ribs 16 on the link 13. The structure of the locating finger 18 is such that it extends between the single loop 11 and the extracting groove 20 in the cartridge 15, overlying or bridging the loop 13 of an adjacent link 10. Since the finger 18 is located on the single loop 11, it can be made substantially longer than would be the case had it been located

on the loop 13. The finger thus has greater cartridge-engaging effectiveness and increased resiliency. Both of these features are important: the first because it is essential that the cartridge be accurately located in the link, and the second because it is just as essential that there be no unnecessary interference with the extraction of the cartridge.

The ammunition belt made up of the links shown in Fig. 3 comprises a plurality of links 30, each of which has a body or bridge portion 31 formed at one side thereof with an integral, single, connecting or hinge loop 32 and at the other side thereof with a pair of coaxially spaced apart cartridge-holding loops 33 and 34. The loops 33 and 34 are respectively similar to the loops 13 and 14 of the link of Fig. 1 and are respectively provided with a pair of external circumferential reinforcing ribs 35 and ribs 36. The single loop 32 is similar to the loop 11 of the link of Fig. 1 but differs therefrom with respect to the positioning and functioning of the cartridge-locating means. The numeral 37 in Figs. 3 and 4 designates a cartridge having a rear or base portion formed with an extracting groove 38 and a forward or neck portion having a frusto-conical shoulder 39. The locating means on the link 30 comprises a forwardly extending finger 40 preferably formed integral with the single connecting loop 32 and extending forwardly therefrom for a distance sufficient to overlie or bridge the forward loop 34 of an adjacent link. The free forward end of the finger 40 is bent downwardly as at 41 and cooperates with the shoulder cone 39 of the cartridge 37 to define the axial extent to which the cartridge 37 is to be inserted in the belt. The finger 40 is formed intermediate its ends with a pair of axially spaced transverse grooves 42 that accommodate or interfit with the circumferential ribs on the forward loop 34 and the function thereof is the same as that of the grooves 21 on the finger 18 of the Fig. 1 link.

Because of the increased length and the ridges 42 obtained in the finger 40 by virtue of its location on the single loop 32, the finger has greater cartridge-locating effectiveness and has increased resiliency that permits free extraction of the cartridge 37.

In the case of either of the forms of link illustrated herein, extraction of the cartridge can be made either forwardly or rearwardly. When extraction is accomplished forwardly by pushing the cartridge from the belt shown in Fig. 1, there is no interference between the locating finger 18 and the cartridge, once the cartridge has been moved axially forward. In the event that the cartridge 15 is extracted rearwardly by pulling, the increased resiliency of the finger 18 obtained by mounting the finger on the single loop 17 precludes the possibility that undesired interference with extraction will occur. The same general conclusions apply with respect to the belt structure shown in Figs. 3 and 4.

With respect to either form of the invention herein disclosed, it will be seen that an improved cartridge belt link has been provided and that such link incorporates features of construction and function that adapt either link for use in weapons in which extraction of the cartridges is either forwardly by pushing or rearwardly by pulling. It will be appreciated of course that only preferred embodiments of the invention have been illustrated and described and that numerous modifications and alterations may be made therein without departing from the spirit

and scope of the invention as defined in the appended claims.

What is claimed is:

1. In an ammunition belt of the type made up of a series of like links articulately interconnected by a series of cartridges, a belt link comprising a body, a single cartridge-receiving loop on the body at one side thereof, a pair of cartridge-receiving loops on the body at the other side thereof and spaced apart coaxially on an axis paralleling the axis of the single loop a distance slightly greater than the axial width of said single loop to receive coaxially therebetween the single loop of an adjacent similar link, means on at least one of the loops of the pair of loops forming an external circumferential rib, and means on the single loop for locating a cartridge received by the single loop and the cooperating pair of loops of an adjacent similar link, the means including a finger member projecting in a generally axial direction from the single loop and including a portion formed to engage a cartridge, the member being constructed and arranged to bridge one of the loops of the pair of loops on an adjacent similar link and including means forming a circumferentially directed groove or recess to accommodate the external rib on the aforesaid one of the pair of loops on the adjacent link.

2. In an ammunition belt of the type made up of a series of like links articulately interconnected by a series of cartridges, a belt link comprising a body, a single cartridge-receiving loop on the body at one side thereof, a pair of cartridge-receiving loops on the body at the other side thereof and spaced apart coaxially on an axis paralleling the axis of the single loop a distance slightly greater than the axial width of said single loop to receive coaxially between them the single loop of an adjacent similar link, and means on the single loop for locating a cartridge received by the single loop and the pair of loops of an adjacent similar link, the means including a finger member projecting in a generally axial direction from the single loop and including a portion formed to engage a cartridge, the member being constructed and arranged to bridge one of the loops of the pair of loops on an adjacent similar link.

3. In an ammunition belt of the type made up of a series of like links articulately interconnected by a series of cartridges that have rear or base portions and front or neck portions, a belt link comprising a body, a single cartridge-receiving loop on the body at one side thereof, a pair of cartridge-receiving loops on the body at the other side thereof and spaced apart coaxially on an axis paralleling the axis of the single loop a distance slightly greater than the axial width of said single loop to receive coaxially therebetween the single loop of an adjacent similar link, and means on the single loop for locating a cartridge received by the single loop and the pair of loops of an adjacent similar link, the means including a finger member projecting axially in a generally axial direction from the single loop and including a portion formed to positively engage the extracting groove of a received cartridge the finger member being constructed and arranged to bridge an adjacent one of the loops of the pair of loops on an adjacent similar link, and means forming a circumferentially directed groove or recess on said member to accommodate at least a portion of the said adjacent loop to position same axially

while permitting relative articulation of said adjacent loops.

4. In an ammunition belt of the type made up of a series of like links articulately interconnected by a series of cartridges that have extracting grooves at their rear or base portions, a belt link comprising a body, a single cartridge-receiving loop on the body at one side thereof, a pair of cartridge-receiving loops on the body at the other side thereof spaced apart coaxially on an axis paralleling the axis of the single loop a distance slightly greater than the axial width of said single loop to receive coaxially therebetween the single loop of an adjacent similar link, means on at least the rearward one of the loops of the pair of loops forming an external circumferential rib, means on the single loop for locating a cartridge received by the single loop and the pair of loops of an adjacent similar link, the means including a finger member projecting rearwardly in a generally axial direction from the single loop and including a portion formed to engage the extracting groove of a cartridge, the member being constructed and arranged to bridge the rearward one of the loops of the pair of loops on an adjacent similar link, and means forming a circumferentially directed groove or recess in the member to accommodate the external rib on the rearward loop on the adjacent link.

5. In an ammunition belt of the type made up of a series of like links articulately interconnected by a series of cartridges that have extracting grooves at their rear or base portions and tapered shoulders at their front or neck portions, a belt link comprising a body, a single cartridge-receiving loop on the body at one side thereof, a pair of cartridge-receiving loops on the body at the other side thereof spaced apart coaxially on an axis paralleling the axis of the single loop a distance slightly greater than the axial width of said single loop to receive coaxially therebetween the single loop of an adjacent similar link, means on at least the forward one of the loops of the pair of loops forming an external circumferential rib, means on the single loop for locating a cartridge received by the single loop and the pair of loops of an adjacent similar link, the means including a finger member projecting forwardly in a generally axial direction from the single loop and including a portion formed to engage the tapered shoulder portion of a cartridge, the member being constructed and arranged to bridge the forward one of the loops of the pair of loops on an adjacent similar link, and means forming a circumferentially directed groove or recess in the finger to accommodate the external rib on the forward loop of the adjacent link.
